MACHINE FOR PLANING METAL SHEETS

Thomas Jerome Massé, Alexandria, near Sydney, New South Wales, Australia, assignor to The Edes Manufacturing Company, Plymouth, Mass., a corporation of Massachusetts

Application July 28, 1939, Serial No. 286,952
In Australia March 30, 1939

21 Claims. (Cl. 90—25)

This invention relates to new and useful improvements in machines for planing metal sheets, particularly sheets of zinc, copper, or other non-ferrous metal such as used for photo-engraving plates, so as to produce semi-finished or finished sheets having a highly uniform thickness over their entire area. The invention relates specifically to improvements in machines of the type disclosed and claimed in my co-pending application, Serial No. 133,740, filed March 29, 1937, 10 which issued as United States Patent No. 2,216,538 on October 1, 1940.

As disclosed in the said co-pending application, I have heretofore provided a new type of machine for bringing zinc or copper sheets to a definite thickness that is uniform throughout the entire area of the sheets. This machine, among other things, includes a massive carriage mounted for movement in a true linear path beneath the path of a fast moving cutting tool or tools, the carriage having a trued upper surface and means for holding one or more sheets thereon with the entire surface of the sheet exposed. The cutting tool is preferably a diamond cutter. It is secured to a rotary head fastened on the end of a nearly vertical spindle, and means are provided for revolving the spindle at high speed so as to move the tool constantly in a true circular path overlying the carriage surface, at a speed of at least several thousand feet per minute. The path of the tool includes a minor circular arc which extends transversely with respect to the path of the carriage, entirely across the sheet or sheets thereon, and truly parallel to the surface of the carriage. Means are provided for traversing the carriage in its linear path beneath the cutting path of the tool at a rate such that successive swaths of the tool, across the surface of the sheet, overlap.

These new sheet surfacing machines are used to bring metal sheets to a highly uniform thickness, within a tolerance of less than five ten-thousandths of an inch—a kind of uniformity that had not previously been attainable in the commercial production of photo-engraving plates. In prolonged practical operation of the machines as heretofore constructed, however, obstacles have been encountered which tend to interfere with the desired efficiency of operation, among which the following are notable:

The vertical spindle of the machine, which carries the rotary head and diamond cutters, is subject to vibration, and to minimize vibration the spindle has heretofore been mounted in bearings which permit no slack or movement in axial

5 or lateral direction during the course of a planing operation. The desired accuracy in the thickness in the planed sheets is not always attainable because very small variations in temperatures are liable to cause objectionable slackness or objectionable tightness in the bearings, with the result that vibration is transmitted to the diamond tools and the vertical position of the diamond tools with respect to the work sheet is disturbed. Also, notwithstanding elaborate provision for lubrication, seizure of the spindle in its closely-fitted bearings is liable to occur, and the bearings tend to wear in such manner as to affect the accuracy of the product. It has been found, for instance, that after the machine has run for several hours with satisfactory results it may cease to do so because of slight displacement of the spindle in axial direction, such displacement changing the depth of cut, and therefore the thickness of the planed sheets, to an objectionable extent. When tolerances in the sheet thickness are limited within one thousandth of an inch and extreme uniformity in the flatness and surface finish of the sheets is required, it has been found difficult to maintain a continuous output of products meeting these requirements.

Furthermore, since surface bearings have been used to carry the heavy axial load of the spindle 30 and the tool head, there is risk of frictional heat being generated in the surface bearings, and "ringing" in those bearings occurs notwithstanding recourse to efficient lubricating systems.

Another objectionable feature of the earlier 35 machines is that it has been necessary to stop the machine in order to return the carriage to its starting point to permit the removal of the planed sheet and the setting of another sheet on the carriage. When the machine is stopped, 40 however, the temperature conditions affecting its operation change rapidly. The temperature changes resulting from a stop of five minutes makes it necessary to run the machine idle for over twenty minutes in order to bring the temperatures up to the normal running point; otherwise, the new work sheet will be planed thicker 45 at one end than at the other. The lost operating time of nearly half an hour is substantial, because the output of the machine per working day is substantially decreased. This difficulty 50 obviously cannot be met by removing and resetting the diamond tools because the degree of accuracy necessary for such a resetting to correspond with the previous setting is not attainable, apart from the fact that a similar time

loss would be occasioned in the tool resetting operation. Accuracy with respect to the previous setting is not attainable because the temperature conditions and the expansion of the parts are not constant owing to cooling down of the parts during the setting operation. With the diamond tool set accurately to plane sheets to the desired thickness within a tolerance of one thousandth of an inch the machine must be run idle for over two hours before the day's planing operations begin in order that the temperatures in the machine parts will rise to and be kept at a constant point while the machine is in operation, the room temperature throughout that time being maintained approximately constant.

Another difficulty that has been experienced with the earlier machines is attributable to the mounting of the work table or carriage on which sheet is held during the planing operation. The carriage has been mounted to slide on two rails which are part of the bed structure of the machine and are trued parallel with the same degree of care as is exercised, for instance, in the finishing of a lathe bed. The carriage slide faces are fitted to the bed rails. The machine bed, however, is necessarily of quite large area, as also is the carriage surface, for in practice engraver's sheets of conventional size measure 20 x 40 inches, and it is often desirable that the carriage surface be capable of holding two of these sheets side by side. The carriage surface must be a little larger in area than the sheet, (or two sheets) to be planed, and the rail faces are more than twice as long as the carriage. Having regard to practically unavoidable distortion in the bed and in the carriage after erection of the machine, which may be caused by aging of the metal of which they are constructed, or by temperature variations, or by mechanical imperfections in the bearings, it has been found that the carriage is likely to rock slightly if supported as heretofore on two slide tracks which do not remain perfect. The desired degree of accuracy in the thickness and surface finish of the sheets is not obtained, however, when any substantial rocking movement of the carriage occurs.

The use of these planing machines, as heretofore constructed, has been attended by further difficulty in setting the diamond cutting tool or tools so that the cutting edge will have the desired angle with respect to the surface of the sheet that is being planed.

The present invention is intended to provide improvements or refinements in the construction of the planing machines which will eliminate the above mentioned and other objectionable features that have been encountered in the practical operation of the machines. An object of the invention is to provide new and improved features of machine construction which increase the efficiency and utility of the machines described and claimed in my aforesaid co-pending application, and to provide certain new features of machine construction which may be used to advantage in other types of metal working machines.

One feature of the present invention is that it provides planing machines of the type described which include improved means for effecting adjustments in the position of the cutting tools with respect to the carriage surface while ensuring movement of the tools in an invariable path during planing operations after an adjustment has been made.

Another feature of the invention is that it provides a new mounting for the carriage on the machine bed, by which to avoid rocking movement or other instability of the carriage.

5 Another feature of the invention is that it provides a planing machine of the type described which is equipped for automatically arresting movement of the carriage at the ends of its path or stroke of movement, together with manually controlled means for bringing the carriage to rest at any desired point in its path.

10 Another feature of the invention resides in the provision of a new type of cutting tool holder for a metal cutting machine, and a new form and 15 mounting of a cutting tool for a metal cutting machine.

Still another feature of the invention consists in the provision of means for moving the cutting tools vertically to and from a position in which 20 the tools are clear of a work sheet on the carriage of the machine. This means also is made responsive to movement of the carriage, so that the cutting tools are raised above the sheet automatically when the carriage has reached the end of its stroke and are lowered to a precisely predetermined cutting position when the carriage has been returned to its starting point.

25 The present invention also provides novel means for protecting the operator of the machine 30 by preventing striking of a work sheet by a cutting tool while the sheet is being placed on the carriage in preparation for a planing operation.

35 The following description sets forth details of a preferred embodiment of the invention, with reference to the accompanying drawings in which such embodiment is illustrated.

In the drawings,

Figure 1 is a plan view of the machine bed with the slide carriage thereon.

40 Figure 2 is a near side elevation of the machine.

Figure 3 is a detail sectional view of a manual drive-releasing device which acts on an end of a lead screw by which the carriage is driven.

45 Fig. 4 is an end elevation of the machine.

Figure 5 is a sectional elevation of the spindle, the tool head thereon, the spindle drive pulley, and the spindle bearings.

50 Figure 6 is a detail of the ball "point" down-thrust bearing by which the spindle position is adjustable vertically to vary the depth of cut to be made by the diamond planer tools and to permit the spindle to rise to clear the tools from contact with the work sheet.

55 Figures 7 and 8 are miniature explanatory sketches showing in exaggerated proportions the transverse concaving of the carriage surface and the tilting of the spindle and the tool head.

Figure 9 is a partial elevation of the rear side 60 of the machine, as modified to embody safety appliances for preventing movement of the table until vacuum is established in the table chamber and the safety shutter has been raised.

65 Figures 10 and 11 are fragmentary sectional views of a slide valve which controls air exhaust from a Sylphon bellows, the bellows being operatively connected to a downthrust bearing that acts on the top end of the spindle.

70 Figure 12 is a plan view of the sylphon and its associated parts which, together with parts shown in Figures 10 and 11, effect adjustment of the spindle top downthrust bearing.

75 Figure 13 is a top plan of one of the tool holder sockets which is fixed on the periphery of the

rotary head carried on the bottom end of the machine spindle.

Figure 14 is a side elevation of the tool holder socket with a tool holder positioned therein.

Figure 15 is a vertical section along line 15—15 of Figure 13.

Figures 16 to 20 are detail views of the tool holder, showing its construction, and the form of a new type of cutting diamond, and the mounting of the diamond in the tool holder.

Figure 21 is a perspective view of the diamond cutting tool.

Figure 22 is a detail view of a portion of the safety locking device included in the assembly shown in Figure 9.

As illustrated in the drawings, the machine provided by the present invention employs the same general combinations and arrangements as disclosed in my co-pending application, Serial No. 133,740. A horizontal work table or carriage 130 is provided for movement in a fixed linear path on a massive supporting bed 30. The carriage has a trued upper surface thereon and is equipped with means for holding a sheet or sheets on this surface with the upper face of the sheet entirely exposed. The carriage is adapted to be moved linearly beneath the path of one or more diamond tools which are carried by a rotary head 34 and are arranged to be moved in a true circular path including a minor circular arc that traverses the entire breadth of the sheet or sheets held on the carriage. The rotary head 34 is mounted on the end of a spindle 40, and means are provided for revolving the spindle at high speed so that the cutting tool or tools are revolved at a speed of at least several thousand feet per minute. The tools cut into the surface of the sheets held on the carriage in arcuate swaths of accurately predetermined spacing from the carriage surface, and the carriage and the sheets thereon are traversed beneath the fast moving tools at a rate such that successive swaths of the tools overlap. The axis of the spindle and tool head is preferably tilted forwardly to a slight extent so that the backward swath of the tool is clear of the sheets held on the carriage, and the surface of the carriage is concaved in transverse direction, in conformity with the cutting path of the tool, it being essential that the cutting path of the tool be truly parallel to the carriage surface.

Referring to the drawings for details of the illustrated construction, longitudinal tracks 10, 11 and 12 are provided on the machine bed structure 30 and are machined to be truly parallel and horizontal. These tracks are illustrated as flat tracks, but they may be of V-section or inverted V-section or they may consist of cylindrical rods fixed down to the bed. A cast iron work table 130 is arranged for horizontal movement above the bed, and a metal sheet 13, preferably of non-ferrous metal such as brass, copper, zinc or aluminum, is fixed down on the face of the work table. Perforations 14 extend through the sheet 30 and the table top and into the chamber 15 in the table body. A flexible pipe connection 16 extends from the chamber 15 to a vacuum pump (not shown).

As shown in Figures 1, 2 and 4, three slide shoes 17, 18 and 19 are fixed to the bottom of the table or carriage 130 and are accurately fitted to the tracks 10, 11 and 12. Shoe 19 is fitted to run on the middle slide 12, and it is located near one end of the table. Shoes 17 and 18 are fitted to run respectively on the side tracks 10 and 11,

and they are located near the other end of the table. The instability of the work table as heretofore encountered has been remedied by the provision of this three-point slide bearing in the present machine. This mounting of the work table eliminates all risk of rocking movement of the table on the bed.

The work table is arranged to be moved in its linear path by means of a lead screw 20 working in a tapped block 20a which is fixed to the table body. The lead screw is rotatable in end bearings 21 and 22 fixed on the machine bed. The table might, however, be driven by hydraulic action with the control valves operated by mechanism corresponding functionally with the illustrated gear box drive arrangement, to be described below.

A grooved pulley 23 is freely rotatable adjacent one end of the lead screw and is V-belted to a pulley 124 connected with a gear box 125. The gear box is connected directly to a motor 24. A manual lever 25 is linked through a control bar 126 to a lever arm 26, for controlling the gear box 125 to set it for forward drive or for reverse drive or at neutral position, as the case may be. The control bar 126 is armed with tappets 127 and 128, which are engaged by a striker 129, fixed on the side of the table, at end of stroke positions. When the striker engages either tappet it throws lever 26 to neutral position and thus automatically arrests the drive when the table reaches either end of its path or stroke. A crank 27 having a handle 28 permits manual movement of the table independently of the motor drive, as may be required; a spring-held bolt 29 is provided for releasing the crank 27 from the pulley 23 while the gear box is set at neutral. By manually throwing the lever 25 to neutral position during either forward drive or reverse drive, the table can be brought immediately to rest.

The table surface is straight in longitudinal direction, but it is concaved transversely, as indicated in Figure 7, and the spindle (and the tool head which it carries) is tilted forwardly as indicated in Figure 8, both Figure 7 and Figure 8 showing the concavity and the tilting to an exaggerated extent for clarity of illustration. It is to be noted that the concaving of the table surface and the tilting of the spindle are features which are set forth and claimed in the copending application, Serial No. 133,740, and they are therefore not claimed in themselves as novel features of the present application.

The table surface on which the work sheets are carried is machined in situ with diamond tools 39 fixed in the tool holders 37. The head carries on its periphery two or more tool holder sockets 35 spaced symmetrically apart, thus incidentally to obtain dynamic balance. As seen in Figures 1 and 8, two tool holder sockets are disposed diametrically opposite. The tilt in the axis of the spindle and tool head is just sufficient to cause the tools to plane the table transversely while causing the table surface to be concaved, for example, about fifteen thousandths of an inch. The details of the tool holder sockets, the tool holders, the diamond tool, and the setting of the diamond tools are described below with reference to Figures 13 to 20 of the drawings.

The body of the table may be an iron casting. It is sheeted with the sheet 13 of non-ferrous metal (preferably brass or copper) which is fixed down on it closely, for example, by screws. It is not practicable to machine a cast iron face satisfactorily with a diamond tool at the cutting speed

at which the machine is operated normally. The machining of the sheeted surface of the table to make it conform precisely to the path of the cutting tools should be effected by the machine itself, with diamond tools adjusted in the tool head and the machine driven at substantially the normal running speed which is used in planing rolled sheets thereon. This condition is important because the table surface on which the work sheets are held during planing must correspond in contour with the swath cut which will be made on the work sheets, thereby to ensure uniformity in the thickness of the planed work sheets. If the machining of the table surface is effected at speeds substantially different from those used in normal operation of the machine, the surface may not be as truly parallel to the cutting path of the tool as desired during a planing operation, and the optimum accuracy in the thickness of the work sheets may not be obtained.

In some types of work the planing of the sheets is effected with a single diamond, while in other types of work two or even four diamonds are used on the rotary head, so that a greater depth of cut may be made in a short period of time and so that at least one diamond is available to remove strain-hardened metal which may be left behind the heel of another diamond.

Upon the heavy bed 30 of the machine a bridge member 31 is straddled. This bridge member carries surface bearings for the spindle, 32 being the upper or neck bearing and 33 a shoulder bearing immediately above the tool head 34. The tool head is a circular disc of aluminum, aluminum alloy, or other light metal. It is desirable that its weight be low in order to minimize risk of vibration. Each tool holder socket 35 is attached to the periphery of the head 34 by screw pins inserted through holes 36. A tool holder 37 may be held in each socket by a set screw 35a. An adjusting screw 35b is provided on a bracket piece 35c for lowering the vertical position of the tool holder in its socket. A diamond cutter 38 is fixed in the bottom end of each of the holders 37. The sockets 35 permit adjustment of the tool holders or stocks 37 in them about a substantially vertical axis, so as to set the cutter edges at any desired angle of contact with respect to the edge of the work sheet on the carriage or work table 130.

According to a special feature of the present invention, the tool 38 is mounted on the head 34 in a novel manner which allows any desired setting of the tool with respect to the work sheet to be effected without disturbing the mounting of the tool itself. In addition, a novel form of cutting tool and a novel mounting therefor are provided, which ensure safe and secure holding of the diamond, protect its edges against chipping and relieve it of strains such as not infrequently cause diamonds to break when mounted according to past practices.

As illustrated in Figures 16 to 20, inclusive, the stock of the tool holder 37 is reduced in diameter at its lower end and is provided with a transverse bore 37a through which extends a closely fitting rotary barrel 37b of a tool clamp device 37c. The barrel is threaded at one of its ends, and a nut 37d is provided for holding the same securely to the tool holder after it has been turned to any desired position around the axis of bore 37a. The tool clamp device includes a base member 37e integral with barrel 37b and

10 a removable clamp member 37f. A tool cavity 37g is formed in the base member to receive the cutting diamond. A guide element 37h extends between members 37e and 37f to align the latter in proper position with respect to the former, and a boss 37i is formed on the clamp member 37f in position to engage and hold a tool in the cavity 37g when the clamp member is secured to the base member by means of a clamping screw 10 37j.

This construction and arrangement of the tool holder 37 permits the cutting tool 38 to be clamped securely in the clamp device 37c in any convenient position which will expose its cutting edge, without regard to any particular setting of the diamond in relation to the work sheet. A precise setting of the angle between the tool face and the edge of the work sheet may be made by turning and locking the tool holder stock in its 15 socket 35. The angle between the cutting edge of the tool and the surface of the work sheet may be adjusted precisely to any desired angle merely by turning the clamp device 37c and barrel 37b in bore 37a, whereupon nut 37d is tightened and 20 the setting operations are complete. Thus any desired variation in the working position of the tool with respect to the work sheet may be effected without unclamping the tool.

A further feature of this construction is that 25 the cavity 37g is made tapered, preferably, conical in form, and the cutting diamond 38 is ground with a correspondingly shaped base 38a. The face of the diamond, as seen in Figure 19, is substantially vertical to the axis of rotation 35 of the clamp device, and this face terminates in a plurality of distinct cutting edges 38b, there being four cutting edges in the illustrated form. In setting the diamond in the clamp device, a film of cushioning cement 39 is placed in the 30 cavity 37g, and the conical base of the diamond is then inserted into the cavity. When the boss 37i is pressed tightly against the central portion of the diamond face by the turning of screw 37j, the tapered form of the diamond and of its 35 support, aided by the film of cushioning cement, distributes the pressure on the diamond evenly over a comparatively large supporting surface, and danger of cracking the diamond is greatly alleviated. When one cutting edge of the 40 diamond is exposed for cutting, as seen in Figures 19 and 20, the other cutting edges are enclosed within the clamp device and are thus protected against chipping. When the exposed edge has 45 been worn or chipped so that it is no longer useful, the diamond need not be discarded but, instead, the clamp member 37f is loosened and the diamond is turned in its cavity to expose another 50 cutting edge.

The adjustments of the tool positions must 55 remain undisturbed once they are accurately set in order that uniformity in the planing finish may be preserved. The tool holders having been adjusted in their mountings on the head 34, the 60 depth of cut which the tools will make is established according to the present construction by precise adjustment of an axial thrust bearing on the top end of the spindle, as described herein-after. In addition, the present machine is provided with means permitting the spindle and 65 diamond cutters to be raised sufficiently to clear a work sheet on the carriage, and means preferably are provided for automatically moving the cutters to and from such a raised position at the ends of the table stroke.

Above the spindle neck bearing 32 is a ball

thrust bearing 41 (Figure 5) one race of which is fixed to the spindle and the other non-rotary race of which is seated on a ring 42. The ring 42 is integral with an upper centering cup member for an annular nest of helical springs 44. These springs are assembled in compression between the upper cup member and a lower centering cup 43, which is supported on upthrust framework of the main bridge 31. A lock nut 45 is screwed on the spindle and bears on the top side of the inner ball bearing race, this fixing the ball bearing and upper centering cup to the spindle. A lock collar 46 holds the lower centering cup 43 in place. The whole weight of the spindle and its associated parts is supported on the ball thrust bearing 41, which reacts against the supporting framework through the cushioning springs 44. In this way the spindle is resiliently mounted and is constantly urged upwardly toward a position in which the diamond tools 38 on head 34 would be clear of the work sheet.

A spherical or V-cup is provided on the top end of the spindle 40 and a hard steel ball 51 is seated in this cup. A cylindrical box 52 is fixed on the top side of the bridge 31. This box is slotted through diametrically, as shown at 53, and a "floating" metal block 54 is placed in it; cross arms 55 are fixed in this block, and they protrude into the slotways 53 and check the block 54 so that it cannot rotate. The block 54, however, is free for vertical movement and for lateral movement in the box 52. A spherical cup 57 is formed in the lower end of the block 54, fitting the ball 51. An adjusting screw 60, tapped through the top end of the box 52, has a spherical point 60a at its lower end which bears against the upper end of the floating block 54. With this novel arrangement the spherical point 60a holds the spindle assembly downward in a constant vertical position, against the compression of springs 44, and the path of the tools carried by the tool head 34 may be changed accurately by merely turning the screw 60. Since the floating block 54 has freedom for a limited amount of lateral movement, it ensures true seating of the spindle top end and takes care of any lateral movement caused by imperfect alignment of the spindle axis with respect to the spherical point 60a. Thus, the axial adjustment of the spindle 40 is effected by turning of the screw 60, the thrust being taken on the spherical point of the screw. The load of the spindle, however, is taken on the ball bearings 41. The upward pressure on the hard steel ball 51 is not enough to cause the degree of friction which would produce heating at this spherical point.

A lever handle 61 is fitted on the head of the screw 60. This lever has a limited degree of movement between two checks 62 and 63 (Figure 6). When the lever is in contact with one of them the spindle is raised sufficiently to clear the diamond cutters 38 from the face of the work sheet. When the lever 61 is moved over into contact with the other check 63 the spindle is forced downward to a predetermined position against the compression of the springs 44, so that the tool is brought down to the position which it must occupy in order to plane the work sheet to a predetermined required thickness. The position of the check pins 62 and 63 may be changed to permit any desired setting of the screw 60 by means of a split collar arrangement 65, upon which the check pins are mounted. The split

collar 65 is carried rotatably on the top end of the box 52, and is adapted to be held in any adjusted position by a clamp controlled by the handle 65a.

5 Since the neck and shoulder bearings 32 and 33 have a tendency to wear, which in time would result in slight but objectionable movement of the spindle away from a fixed vertical axis, these bearings are equipped with means 32a and 33a, 10 of known construction, for effecting periodic tightening of them around the spindle.

As shown in Figure 12, the lever handle 61 may have a pivotal connection 161 to stem 162 of a Sylphon bellows 68 and to an opposing tension spring 69. The cylinder 68 is connected through a pipe 71 to a slide valve 72 which is connected by a pipe 73 to a vacuum chamber. The valve 72 is operated by the rod 126 (see Figure 1). At full stroke position of the work 20 table, rod 126 is pushed forward by contact of the striker 129 on the table, and it thus opens valve 72 to suction, and air is educted from the Sylphon 68; and Sylphon 68 thereupon pulls the lever arm 61, turns the screw 60 upwards, and 25 permits the spindle 40 to rise, thus lifting the head 34 and so raising the diamond tools clear of the surface of the work sheet. At the end of the reverse movement of the table, air is admitted to the Sylphon through the valve 72, which 30 has now been reversed, and the spring then acts to turn the thrust screw 60 down and thus lower the spindle 40 and so bring the diamond tools into predetermined cutting position with respect to the surface of the work sheet. The tool 35 position is therefore brought down to planing level automatically at the start of the table forward movement, and it is raised automatically at the completion of that movement.

While the operator is setting a new work sheet on the table, it would be possible for him to push the sheet too far forward so that it would be struck by the tools, which are in movement at high speed. To prevent that accident, which might have serious consequences, a safety guard is provided. This guard is a downfolding shutter 100 which is suspended pivotally at 101 from fixed brackets 102 above the leading end of the machine table. This shutter prevents a work sheet from being pushed past it. An arm 103 with lost motion is carried on the axle 104 on which the shutter 100 is suspended; this arm 103 is connected by a link 105 with one end of a fulcrumed lever 106, and the other end of that lever carries a bolt 107 which is slideable vertically in a guide casing 108. This bolt 107 45 contacts with another bolt 109 which is normally forced down by a spring 110 into engagement with it. The bolt 109 is carried by a Sylphon bellows 111 which is fixed on one side of the machine table and is connected into the vacuum 50 chamber 115 in the table body. When connection from the vacuum pump to the chamber 115 is open to atmosphere, as is required to permit removal of a planed sheet from the table, the bolt 109 is forced down by the spring 110 so that it then engages the bolt 107. The table is then at the full back position and it is checked against forward motion by these bolts. If by misadventure the motor drive should be applied while the 55 table is so checked, a friction clutch which is contained in the pulley 124 slips, and the table is not driven. The lower bolt 107 remains engaged with the Sylphon-operated bolt 109 until a new work sheet has been set down on the table and vacuum applied to the chamber 115 to hold

it close down on the table surface, and until the shutter 100 has been tilted up to the position shown in dotted lines and the bolt 107 has been thereby drawn full down out of the path of the coating bolt 109. At the completion of the planing of a sheet and return of the table to the starting position the shutter 100 is dropped down to the full line position (see Figure 9), thus setting the bolt 107. Until both bolts 107 and 109 have been fully retired the table remains checked by them against forward movement. When a new work sheet has been placed on the table and held down thereon by vacuum in the chamber 15, operating through the perforations 14, and the shutter 100 has been raised, the table becomes automatically released for forward movement. Retirement of one of the check bolts (107, 109) without withdrawal of the other leaves the table locked against movement, notwithstanding that the spindle remains in rotation. In practice the spindle is kept in rotation during arrests of the table movement in order to avoid disturbance of temperature conditions in its bearings.

A hole runs through screw 60 axially and lines up with a center hole in the floating block 54; this hole is extended through the spherical cup 57, which feeds oil to the ball 51. By introducing lubricant into screw 60 from a cup 70V, lubrication is provided to the axial thrust ball 51, and the overflow of lubricating oil runs thence downward through the ball bearing 41 and into the bearing 32. The bearing 32 is also lubricated by vertically extending wicks which receive their oil from a cup 70V. Oil leakage from the bottom of bearing 32 is gathered in the collar 80 and is led away through a leak pipe 81. A shed collar 12 directs this oil drainage into the gutterway in the collar 80. The shoulder bearing 33 is wick lubricated through the cup 70X (Figure 2), and the oil which leaks down from that bearing passes out over the shed collar 85 into the gutter collar 86, whence it is turned away through the leak pipe 87. The flange 40X (Figure 5) on the spindle 40 immediately below the shoulder bearing 33 limits the range of upward movement of the spindle.

A screw having a spherical end may be used in substitution for the ball 51. It is important, however, that the downward thrust of the adjusting screw 60 on the spindle 40 be applied through a "frictionless" point contact, which may be either a hard steel ball or a spherical end member taking its bearing on the top end of the spindle, with provision made for a very small amount of centering movement as, for instance, by means of a member such as 54. The spindle 40 is driven, for example, by a belt extending between a pulley 58 on the spindle and a motor-driven pulley 58a.

In the planing of rolled zinc sheets for engravers' plates the spindle is driven at a speed which moves the diamond tools over the sheets at a speed of at least several thousand feet per minute. A speed of about 8000 feet per minute is preferred. For zinc that speed may be substantially increased or diminished, according to the judgment of the operator. For metals other than zinc the speed for best operation should be determined by test on a trial sheet, and in the case of certain metals it may be as low as 4000 feet per minute.

It will be understood that the present invention is not restricted to the details of construction which are described herein for clarity of illustration, but that it extends to all equivalent

features and constructions within the spirit of the disclosure and the scope of the appended claims.

I claim:

- 5 1. In an apparatus for machining metal including a movable work table, means for holding work to be machined on said table, a spindle rotatable in bearings above said table, a tool head fixed on one end of said spindle and at least one tool secured to said tool head, mounting means for said spindle comprising a thrust bearing and cushioning spring means on which the axial load of the spindle is supported in compression and adjustable means for applying downward pressure to the top end of the spindle in opposition to the upward thrust of said cushioning spring means.
- 10 2. In an apparatus for machining metal including a movable work table, means for holding work to be machined on said table, a spindle rotatable in bearings above said table, a tool head fixed on one end of said spindle and at least one tool secured to said tool head, mounting means for said spindle comprising a thrust bearing and cushioning spring means on which the axial load of the spindle is supported in compression and adjustable means for applying downward pressure to the top end of the spindle in opposition to the upward thrust of said cushioning spring means, said adjustable means comprising a self-centering point bearing and means for adjusting the same in vertical direction.
- 15 3. In an apparatus for machining metal including a movable work table, means for holding work to be machined on said table, a spindle rotatable in bearings above said table, a tool head fixed on one end of said spindle and at least one tool secured to said tool head, mounting means for said spindle comprising surface bearings respectively embracing different portions of the tool head spindle and holding said spindle for rotation about a fixed axis, a thrust ball bearing having a rotary race secured to said spindle and a non-rotary race supported to sustain the axial thrust of said spindle and tool head, a compression spring cushion and means for transmitting the load of the spindle and tool head onto the support for said bearing through said spring cushion.
- 20 4. In an apparatus for machining metal including a movable work table, means for holding work to be machined on said table, a spindle rotatable in bearings above said table, a tool head fixed on one end of said spindle and at least one tool secured to said tool head, mounting means for said spindle comprising surface bearings respectively embracing different portions of the tool head spindle and holding said spindle for rotation about a fixed axis, a thrust ball bearing having a rotary race secured to said spindle and a non-rotary race supported to sustain the axial thrust of said spindle and tool head, a compression spring cushion positioned to transmit said thrust to the support for said bearing, a spherical end thrust bearing acting on the top end of said spindle, a floating non-rotary seat for said end thrust bearing and means for applying downward pressure axially on the spindle through said seat and spherical bearing to effect axial adjustment of the spindle by compressing said spring cushion.
- 25 5. In an apparatus for machining metal including a movable work table, means for holding work to be machined on said table, a spindle rotatable in bearings above said table, a tool head fixed on one end of said spindle and at least one

tool secured to said tool head, mounting means for said spindle comprising surface bearings respectively embracing different portions of the tool head spindle and holding said spindle for rotation about a fixed axis, a thrust ball bearing having a rotary race secured to said spindle and a non-rotary race surrounding the spindle, a stationary support for supporting the load on said thrust bearing, an annular series of compression springs seated on said support, and means integral with said non-rotary race for resting the same on said compression springs whereby adjustably to support the load of said spindle and tool head through said compression springs.

6. In an apparatus for machining metal including a substantial vertical spindle and means for rotating the same at high speed, mounting means for said spindle comprising surface bearing means adapted to hold said spindle for rotation about a predetermined axis, a thrust bearing and compression spring means for sustaining the axial load of said spindle, a self-centering end thrust bearing acting on the upper end of said spindle to limit upward movement of the same under the influence of said spring means, and adjustable means for varying the vertical position of said end thrust bearing whereby to regulate the vertical position of said spindle.

7. In a metal sheet planing machine including a horizontal slide bed, a planing table slidable along said bed, means for holding a sheet of metal on the surface of said table, a nearly vertical spindle rotatable in bearings above said table, a tool head fixed on one end of said spindle and at least one cutting tool secured to said tool head, mounting means for said spindle comprising surface bearings respectively embracing different portions of the tool head spindle and holding said spindle for rotation about a fixed axis, a thrust ball bearing having a rotary race secured to said spindle and a non-rotary race supported to sustain the axial thrust of said spindle and tool head, a compression spring cushion, means for transmitting the load of the spindle and the tool head onto the support for said bearing through said spring cushion, a single point self-centering end thrust bearing acting on the top end of the spindle, a floating seat for said end thrust bearing and means for applying downward pressure axially on the spindle through said seat and point to effect axial adjustment of the spindle by compressing said spring cushion so as thereby to adjust the depth of cut to be made by the tool.

8. In a metal sheet planing machine including a horizontal slide bed, a planing table slidable along said bed, means for holding a sheet of metal on the surface of said table, a nearly vertical spindle rotatable in bearings above said table, a tool head fixed on one end of said spindle and at least one cutting tool secured to said tool head, mounting means for said spindle comprising means for supporting the same under spring compression in axial direction while maintaining movement of said cutting tool in a fixed path during a planing operation and means for changing the axial position of the spindle with respect to the carriage surface while the spindle is rotating to permit the path of the cutting tool to clear the surface of a sheet held on said table surface.

9. In a metal sheet planing machine including a horizontal slide bed, a planing table slidable along said bed, means for holding a sheet of metal on the surface of said table, a nearly ver-

tical spindle rotatable in bearings above said table, a tool head fixed on one end of said spindle and at least one cutting tool secured to said tool head, mounting means for said spindle including a spring cushioned ball thrust bearing for supporting the tool head spindle resiliently in axial direction, a self-centering point on the spindle and adjustable means for applying downward pressure in axial direction on said point in opposition to the upward support of the spindle on said spring cushioned thrust bearing for varying the tool clearance with respect to the table on which the work is held.

10. In a metal working machine including a horizontal slide bed and a massive work table slidable along said bed, a plurality of laterally spaced parallel slide tracks on said bed and three triangularly spaced slippers fixed to the under side of said table and fitted to rest and slide on said tracks.

11. In a sheet metal planing machine in which the work sheet is held on a table which is traversable under a rotatable head which carries a cutting tool, a slide rail bed having three parallel slide tracks spaced laterally apart and three slippers fixed to the under side of the table and respectively fitted to run on said slide tracks, two of said slippers located at or near one end of the table and working respectively on the outer slide tracks, and the third slipper located at or near the other end of the table and working on the middle slide track.

12. In a metal sheet planing machine including a horizontal slide bed, a planing table slidable along said bed, means for holding a metal sheet on the surface of said table, a nearly vertical spindle rotatable in bearings above said table, a tool head fixed on the bottom end of said spindle and at least one cutting tool secured to said tool head, said bed comprising three trued horizontal slideways arranged in parallel and spaced relation and said table having three slippers mounted on the under side thereof and supported slidably on said slideways, two of said slippers being spaced apart and slideable respectively on the outer slideways and the third slipper being slideable on the middle slideway.

13. A sheet metal planing machine comprising a horizontal bed having a plurality of slideways on its top surface, a work table slideable on said slideways, said table surface being concaved transversely, means for holding a sheet to be surfaced with one face of the sheet in contact with said table surface and the other face thereof entirely exposed, means for traversing said table along said slideways under a bridge which is built on the machine bed, surface bearings in said bridge radially supporting a spindle in said bridge, a tool head fixed on the foot of said spindle and a plurality of diamond tool holders demountably fixed on the peripheral part of said tool head, said spindle being tilted slightly forwardly from the vertical so that the cutter swath on the work sheet is concave in correspondence with the transverse concavity in the table surface, an axial bearing for said spindle independent of said radial bearings, said axial bearing being a thrust ball bearing, a spring cushion sustaining the spindle load on said ball bearing, and an adjustable end thrust self-centering point bearing acting downwardly on the top end of the spindle in opposition to the spring cushion support, means for applying rotation to the spindle, and means for supplying lubricating oil to said bearings.

14. In a sheet metal planing machine of the kind herein described, a downthrust self-centering point bearing at the top end of a spindle which carries a diamond tool head on its bottom end, said spindle being supported in radial surface bearings and by an axial thrust bearing and a spring cushion resting on a common support, said downthrust point bearing comprising a hard steel ball of small diameter seated in a cup in the spindle top end, a non-rotatable pressure block movable in a fixed housing located above the spindle, a concaved contact face in the bottom end of said block accommodating said ball, and a screw tapped through the top of said housing and adapted to be rotated so as to apply downward pressure on said spindle through said block and ball in opposition to the lift applied to the spindle through said spring cushion, whereby to effect axial adjustment of said spindle in said radial surface bearings.

15. In a metal sheet planing machine including a horizontally slideable work table, means for holding a sheet to be planed on the surface of said table, a spindle rotatable in bearings above said table, a tool head fixed on the lower end of said spindle and at least one cutting tool secured to said tool head, a downward end thrust bearing for the vertical spindle in combination with a spring cushioned up-thrust bearing supporting the load of said spindle, said end thrust bearing being a ball self-centering in a cup, and an adjusting screw acting above said cup and adapted to force the spindle downward in its radial surface bearings against the lift of the spring cushion of the up-thrust bearing, whereby to adjust the clearance of the cutting tool with respect to the surface of the work table.

16. In a metal sheet planing machine including a horizontal slide bed, a planing table slideable along said bed, means for holding a sheet of metal on the surface of said table, a nearly vertical spindle rotatable in bearings above said table, a tool head fixed on one end of said spindle and at least one cutting tool secured to said tool head, resilient means for urging said spindle, head and tool to a position in which the tool moves clear of a sheet on said table, adjustable means for lowering said spindle, head and tool to a cutting position in opposition to said resilient means, and means responsive to movement of said table for actuating said adjustable means whereby automatically to move said cutting tool to and from a cutting position.

17. In a metal sheet planing machine including a horizontal slide bed, a planing table slideable along said bed, means for holding a sheet of metal on the surface of said table, a nearly vertical spindle rotatable in bearings above said table, a tool head fixed on one end of said spindle and at least one cutting tool secured to said tool head, resilient means for urging said spindle, head and tool to a position in which the tool moves clear of a sheet on said table, adjustable means for lowering said spindle, head and tool to a cutting position in opposition to said resilient means, means actuated at the end of the sliding stroke of said table for moving said adjustable means and causing the spindle to be

raised by said resilient means, and means actuated when said table has been returned to starting position for moving said adjustable means and lowering said spindle to its original cutting position.

18. A metal sheet planing machine including a horizontal slide bed, a planing table slideable along said bed, driving means for sliding said table along said bed, means for holding a metal sheet on the surface of said table, a nearly vertical spindle rotatable in bearings above said table, a tool head fixed on the bottom end of said spindle and at least one cutting tool secured to said tool head, and means operated by movement of said table for rendering said driving means inoperative and arresting movement of the table at the ends of the table stroke.

19. A sheet metal planing machine including a horizontal slide bed, a planing table slideable along said bed, means for holding a sheet of metal on the surface of said table, a nearly vertical spindle rotatable in bearings above said table, a tool head fixed on one end of said spindle and at least one cutting tool secured to said tool head, means operated by movement of said table for automatically rendering said driving means inoperative and arresting movement of the table at the ends of the table stroke and manually controlled means for rendering said driving means inoperative and bringing the table to rest at any desired point in its stroke.

20. A metal sheet planing machine including a horizontal slide bed, a planing table slideable along said bed, driving means for sliding said table along said bed, means for holding a metal sheet on the surface of said table, a nearly vertical spindle rotatable in bearings above said table, a tool head fixed on the bottom end of said spindle and at least one cutting tool secured to said tool head to move in a fixed cutting swath extending transverse to the path of said table and entirely across a sheet thereon, a shield member movable between the path of said tool and a sheet on said table when the table is located at its starting position and means for preventing movement of the table away from its starting position when said shield member is operative.

21. A metal sheet planing machine including a horizontal slide bed, a planing table slideable along said bed, driving means for sliding said table along said bed, means for holding a metal sheet on the surface of said table, a nearly vertical spindle rotatable in bearings above said table, a tool head fixed on the bottom end of said spindle and at least one cutting tool secured to said tool head to move in a fixed cutting swath extending transverse to the path of said table and entirely across a sheet thereon, a shield member movable between the path of said tool and a sheet on said table when the table is located at its starting position, and means for preventing movement of said table away from its starting position when either said shield member is operative or said holding means has not been made operative to hold a sheet on the table.

THOMAS J. MASSE.
